UNITED STATES PATENT OFFICE.

RONALD F. McFEELY, OF BEVERLY, MASSACHUSETTS, ASSIGNOR TO UNITED SHOE MACHINERY COMPANY, OF PATERSON, NEW JERSEY, A CORPORATION OF NEW JERSEY.

PULLING-OVER MACHINE.

1,135,954.

Specification of Letters Patent. Patented Apr. 13, 1915.

Application filed April 19, 1909. Serial No. 490,848.

To all whom it may concern:

Be it known that I, RONALD F. McFEELY, a citizen of the United States, residing at Beverly, in the county of Essex and State 5 of Massachusetts, have invented certain Improvements in Pulling-Over Machines, of which the following description, in connection with the accompanying drawings, is a specification, like reference characters on 10 the drawings indicating like parts in the several figures.

This invention relates to machines for use in the manufacture of boots and shoes and particularly to a machine comprising 15 mechanism for pulling an upper over a last and adjusting it in proper relation to the last and for thereafter securing the upper in pulled over position.

The present invention comprises improvements upon the machine shown in 20 United States Letters Patent No. 663,777, granted on my application December 11, 1900, and No. 1,029,387, granted on my application June 11, 1912, to which reference 25 may be had for a description of a complete pulling-over machine of this type.

One feature of this invention consists in novel means for clamping and holding the upper after it has been pulled and adjusted 30 and during the time when the grippers are releasing their hold upon the upper and giving place to the tacking mechanism by which the upper is secured.

An object of this feature of the invention 35 is to provide means which can be actuated into position for securely clamping the upper against retrograde movement before the grippers release their hold upon it. It is found in the practical use of this machine 40 that in some shoe factories and occasionally in many factories the uppers are so small with relation to the last that the grippers do not rise in their pulling movement to a 45 position in which they are entirely above the plane of the shoe bottom. In accordance with this invention, therefore, the clamping means is arranged entirely below the plane of the shoe bottom so that it may be moved into position for securely holding the upper 50 before the grippers release it even in instances where the grippers remain slightly below the plane of the last bottom.

Other objects of this feature of the invention are to provide clamping means which

shall, during the clamping operation tend 55 to press the upper in the same direction in which it is tensioned by the pulling grippers and which shall be capable also of securely supporting the shoe against downward pressure. To these ends the clamps 60 each comprise two contact members carried by swinging arms like those in the prior machine. The upper contact member is movable in a horizontal plane and connected to the lower or last supporting member 65 by a pinion, the arrangement being such that the upper member shall first engage the shoe and then through the pinion force the supporting member into engagement with the shoe. The supporting member is arranged 70 to move upwardly and inwardly in this advance toward operative position effected through the pinion. By this arrangement the last supporting member approaches the shoe in a direction inclined toward the 75 direction of pull and assists in tensioning the upper in the same direction in which the grippers have pulled it. Provision is also added for locking the last supporting member against downward and outward movement. This is accomplished by connecting 80 with the pinion that raises the last supporters a ratchet which is engaged by a locking pawl to hold the last supporter rigidly in the position to which it has been raised. A 85 desirable characteristic of this feature of the invention is that the locking pawl is so arranged that it will be automatically released from the ratchet when the clamps move to their inoperative position at the end 90 of the machine's operation. To this end the locking pawls are arranged to swing by reason of their inertia away from the ratchets when the arms carrying the clamps come to rest at the end of their outward 95 movement.

Another feature of this invention is concerned with means for wiping the upper over the last bottom and conditioning it for the reception of the securing tacks. The 100 wiping means at the side of the shoe is shown as arranged to coöperate with the side clamps to some extent in holding the upper. To this end the wiping means is formed as a plate movably attached to the 105 lower face of the tack arm of the machine and arranged to move inwardly over the shoe after the side clamps have come into

firm holding engagement with the upper. The wiper is connected to the tack arms so that it can both rock upwardly and slide in the direction of its length and its front edge 5 is turned upwardly. Yielding means is provided for holding the front edge of the wiper normally in its lowermost and most advanced position and the arrangement is such that the wiper advancing after the 10 clamps have been set, engages the shoe in about the plane of the top faces of the clamps, which is below the plane of the shoe bottom. The upturned or inclined front face of the wiper thus rides up over the 15 edge of the shoe and advances inwardly over the shoe bottom as far as the grippers permit it to move, it being understood that the grippers are at this time allowed by their operating mechanism to swing inwardly 20 over the shoe bottom for overlaying the upper. As the wiper rocks in riding up over the shoe edge the spring actuating it is compressed so that it is caused to press the upper firmly down upon the margin of the 25 shoe bottom. When the wiper has moved inwardly as far as the position of the grippers permits it to do the tack arm continues to advance with relation to the wiper and in this advance movement the spring 30 acting upon the wiper is put under increased tension by reason of the sliding connection between the wiper and that spring so that during this independent movement of the tacker and the wiper the upper is pressed 35 hard down upon the margin of the last bottom to compact it and prepare it for the reception of the securing tacks. The continued advance of the tack arm trips the grippers and causes them to release the upper, whereupon the wiper is quickly projected forwardly to lay the released upper inwardly over the innersole and continue to hold it while the tacks are being inserted. 40 In order that the wiper may operate as described it is desirable that it normally projects some distance inwardly from the tackers. This relation of the wiper to the tackers is liable to be an inconvenience in inserting the shoe in the machine and arranging the upper within the grippers and therefore provision is herein made for retracting the wipers when the tack arms and wipers move outwardly to their inoperative position. To this end means is provided for 45 releasing the wiper from the control of its actuating spring as the tack arms move to their outer position and are abruptly stopped in such position. This allows the wipers to slide backwardly with relation to the tack arms by reason of their inertia as the movement of the arms is suddenly checked.

These and other features of this invention, including certain combinations of 50 parts and more important details of con-

struction, will be explained in connection with the following description of the mechanism in which the invention is shown as embodied and then pointed out in the claims.

Figure 1 is a side elevation of so much 70 of the machine as it appears necessary to show for disclosing the present invention, the toe-tacker which appears in outline therein to complete the illustration of a pulling-over machine being the same as that 75 shown in U. S. Letters Patent No. 1,029,387, and not constituting a part of the present invention. Fig. 2 is a fragmentary view showing in front elevation the side clamps and tack arms, a shoe being shown in section 80 with the upper pulled and held under tension by the side grippers ready to be clamped to the last by the side clamps and overlaid upon the shoe bottoms by the wipers and then fastened by the tacker. 85 Fig. 3 is a perspective view of a side clamp and a tacking mechanism. Figs. 4, 5 and 6 show these parts in different positions assumed during the operation of the machine; Figs. 2, 4, 5 and 6 represent successive steps in clamping, overlaying and 90 tacking an upper at the sides of the shoe.

The upper pulling and adjusting mechanism may be the same as that shown in said prior patents and, specifically, forms 95 no part of this invention. This mechanism does not require to be herein described but reference may be had to said prior patents for further information than that found in these drawings.

The side clamps which take control of the upper at the sides of the shoe after it has been pulled and adjusted and preparatory to the release of it by the side grippers 8. 100 in order that said grippers may give place to the tackers, are carried by properly actuated supports herein shown as swinging arms 10 fulcrumed at 12 and moved together, yieldingly from and toward the shoe. The devices comprised in the side clamps are 105 actuated relatively and are caused to do their work by the movement transmitted to them by the arms 10 by reason of which they are brought into engagement with the shoe. These devices comprised in the clamp mechanism include last supports 15 which are 110 padded blocks swiveled upon slides 16 that are movable in guideways extending obliquely downwardly and outwardly with relation to the shoe. The slides each have 115 toothed engagement with a pinion 20 (Fig. 2) which also engages a toothed slide 22 carrying a second contact member 25 and movable in a horizontal plane in the head of the arm 10. The pinion thus forms a 120 driving connection for moving one of said parts outwardly when the other is moved inwardly and forms an equalizing connection for distributing equally the pressure 125 from the arm actuating means to the slides 130

16 and 22 when the clamping members 15 and 23 carried by the slides respectively are in engagement with the shoe.

The second contact member 25 above mentioned is best shown in Fig. 3 where it may be seen that it has an arc shaped tongue and groove connection with the slide 22 and that it has bearing faces at 24 with a depression or concave surface between said faces. This formation and mounting permit the clamp 25 to obtain bearing against the side of the shoe at two places spaced a little distance apart. In the machine, the side gripper may comprise two pairs of jaws 15 at each side of the shoe as has heretofore been proposed and the contacting or upper clamping surfaces 24 may each coöperate with one pair of jaws to clamp the portion of the upper that is directly in the line of pull of those jaws.

In accordance with this invention the normal position of the last support 15 is as shown in Fig. 2 at the lower limit of its movement to which it is held by a light spring 18 which also acts through the pinion 20 to position the clamp 25 at the inner limit of its movement where it will engage the shoe before the last support engages the shoe. The present arrangement is distinguished from prior constructions in this respect that the clamp 25 engages the shoe before the last support does and, through the pinion 20, moves the last support inwardly and upwardly into supporting engagement with the last. The last support thus has an operative movement upwardly toward, against and along the upper in the direction in which the grippers are straining the upper, the effect of which is that the last support contributes to the tensioning of the upper toward the edge of the last as it comes into bearing position and as it sustains the shoe against downward pressure. It will be understood that the grippers press the shoe upwardly against the shoe bottom rest 23 while they are pulling and holding the upper and that when the grippers release the upper, to give place to the tackers after the side clamps have assumed a relation to the shoe in which they hold the upper from slipping back, the reaction of the bottom rest and its supporting and actuating mechanism tends to press or crowd the shoe downwardly between the last supporters. In order to resist this movement of the shoe as well as to resist the downward thrust of the drivers when they insert the tacks, and to insure that the shoe shall merely be wedged downwardly between rigid last supporters which will effect an additional tensioning of the upper about the last by such downward wedging movement of the shoe, the pinions 20 are each connected to a ratchet 30 with which engages a pawl 32. The pawl locks the last support-

ers in whatever position they are raised and causes them to support the shoe unyieldingly. With this arrangement there is little downward movement of the shoe and such downward wedging as does occur between the last supporters is utilized to secure a tighter upper in the completed shoe. The pawl 32 is held against the ratchet by gravity and is so formed that when the arms 10 swing outwardly to their starting position the pawl is disengaged from the ratchet by its inertia. It is to be noted as characteristic of this construction that the last supporter 15 and the clamp 25 form at each side of the last unyielding means between which and the last the upper is clamped or held before the side grippers need to release the upper and that these clamping members 15, 25 may remain immovable, or do not require to change their position with relation to each other or to the last while they are being depended upon to hold the upper.

The means for wiping the upper over upon the last bottom into position to be fastened includes the wiper 40. This is supported independently of the clamping means above described and acts independently thereof in the sense that the clamping means may receive all of its movements before the wiper begins to act and that the clamping means may remain motionless in holding relation to the shoe, while the wiper does its work. The wiper is shown as carried by the tack carrying arm 42 which is supported and actuated as in said prior Letters Patent No. 663,777.

The wiper carrying block 43 which for convenience is made detachable from the arm 40 is shown best in Fig. 3. The wiper is a plate of thin metal having its front end notched to permit the driving of the tacks through it from the tack pockets above. The front end of the plate is also upturned to a substantial extent to insure that the front edge shall always strike the upper above the shoe bottom or so that it will start the beveled lower face of the wiper to ride over the edge of the shoe.

The wiper is slotted to permit the stem 45 to project through it and is retained on the stem by a cap 46 held in place by a bolt 48. The slot in the wiper is longer than the stem 45 so that the wiper is capable of endwise movement. The space between the cap 46 and the lower face of the wiper carrying block 43 is greater than the thickness of the wiper so that the latter can tilt upwardly. The lower face of the rear portion of the block 43 is inclined upwardly as shown forming an angle at 50 which constitutes a fulcrum with relation to which the wiper has tilting and sliding movement as will be understood from Figs. 4, 5 and 6. The rear end of the wiper is formed with the incline 130

52 and the seat in the rear of the incline for the roll 54 which is carried on the upright rod 55 and held in its uppermost position by the spring 56. This arrangement provides that the wiper can yield backwardly, by sliding on stem 45 and can yield upwardly, by tilting on fulcrum 50, against the tension of spring 56. The wiper advances in the position shown in Fig. 4 but when it engages the shoe its upturned front end rides up over the edge of the shoe bottom, adapting itself to the level of the shoe, and then yields backwardly as shown in Fig. 5 until the advancing arm 42, or the parts carried by said arm, engage the tripping device 9 by which the grippers are caused to release their hold upon the upper. Thereupon the spring 56 acting through the roll 54 on the rear incline 52 impels the wiper forwardly to the position shown in Fig. 6 across the tacking line where it will hold the upper in position for the tacks to be inserted through the notches which show best in Fig. 3. The wiper will be understood to advance with the tack carrying arm 42, and to ride up over the shoe edge until it is stopped, Fig. 5, by the upheld upper after which the arm 42 advances relatively to the wiper and the spring 56 is put under additional tension as the roll 54 rides along incline 52. This reaction of the spring causes the front end of the wiper in engagement with the upper to press the stock down hard upon the last bottom and compact it for receiving the tack. This action of the wiper continues until the arm 42 trips the grippers whereupon the wiper is free to be projected forwardly by the spring 56 and the drivers are then immediately tripped. When the parts return to their starting position a swinging arm 58 that is carried on the tack arm, and has a roll 59, engages an incline 60 on the frame or fixed bracket 62, and is depressed by such engagement. When the arm 58 is thus forced downwardly it depresses rod 55 and roll 54 so that the wiper is free to slide backwardly with relation to the arm. This backward movement is effected as a result of the inertia of the wiper causing it to continue in motion endwise when the return of the arm is checked abruptly by contact with bracket 62 or an adjustable stop 63 therein. This backward movement of the wiper relatively to its carrier is provided to position the wiper out far enough so that it will not interfere with the insertion of the next shoe to be operated upon by the machine and with the arrangement of the upper within the grippers. The swinging arm 58 referred to is hung on the same pivot as a tack conductor 70 which receives tacks from the conductor tubes 72 and delivers them to the tack pockets in the block 43. When the tack carrying arm is swung out as in Fig. 2 the conductor strikes a stop 75

and its lower end is swung upwardly and inwardly to put its passageway into communication with the tack pocket as shown in that figure. It is in this situation that the tacks from the feeding mechanism find their way down the tubes and are delivered to the tack pockets. When the arm 42 swings inwardly the spring pressed plunger 76 having an extended head positions the forward extension 73 of conductor 70 over the mouth of the tack pocket so that the tack in the pocket cannot jump out therefrom or by any accident be displaced therefrom during the movement of the parts into the position over the shoe where the tacks are driven. This arrangement overcomes a difficulty that has been found because the quick inward movement of the arms 42 has sometimes caused the tacks to be thrown out of their pockets or to become so displaced therein that they were not properly driven. The extension 73 forms a cover which is automatically applied and removed. The cover has an inclined upper face which the driver in its descent engages to force the conductor out of the driver path.

The features of this invention embodied in the arrangement for preventing tacks from being thrown out of the tack holders is not claimed in this application but forms the subject-matter of a divisional application Serial No. 520,149.

The manner in which the improvements herein described are to be employed has been made clear in connection with the description of the mechanism in which the invention is herein shown as embodied.

I claim as new and desire to secure by Letters Patent of the United States:

1. A machine of the class described having, in combination, means for pulling an upper over a last, means to fasten the upper, and means to hold the upper while the pulling means gives place to the fastening means, said holding means comprising connected upper clamping devices arranged one above the other in position for the upper one of the devices to engage the shoe first, and actuating mechanism for forcing the lower member obliquely upwardly to press against the upper in the direction in which it is pulled.

2. A machine of the class described having, in combination, side clamps comprising a horizontally sliding member and an obliquely movable member connected therewith and connecting mechanism for causing the horizontally sliding member to engage the shoe first and thereafter to actuate the other member upwardly and inwardly in the direction to press the upper toward the edge of the last as the shoe is clamped.

3. A machine of the class described having, in combination, a carrier movable horizontally toward the shoe, a contact member

arranged to yield backwardly in the carrier after it engages the shoe, and a second member arranged to engage the shoe later and to be actuated upwardly by such backward movement of the contact member to press the upper upwardly toward the edge of the shoe.

4. A machine of the class described having, in combination, means for positioning a shoe bottom upwardly, a last supporter, means for actuating the supporter laterally toward the shoe, means becoming operative automatically during said movement laterally toward the shoe for actuating the supporter obliquely upwardly into contact with the upper on the side of the shoe, and means for acting on the shoe with a tendency to depress the shoe against the supporter.

5. A machine of the class described having, in combination, a shoe bottom rest, grippers to pull the upper, means to tack the upper, and means arranged to engage under the side of the shoe to support the shoe while the grippers release the upper and give place to the tacker, comprising a member for clamping the upper against the side of the last, and means for imparting to said member an operative movement into clamping position in a direction inclined upwardly and inwardly to force the upper in the direction that it is tensioned by the pulling means.

6. A machine of the class described having, in combination, a shoe bottom rest, grippers to pull the upper, and a member that is out of contact with the shoe during the pulling operation and is guided for movement upwardly and inwardly in a direction oblique to the shoe bottom to press the upper toward the edge of the last and then clamp it against the side of the last for holding it while the grippers are released to permit the upper to be fastened and means for effecting the described upward and inward movement of said member to cause said pressing and clamping of the upper.

7. A machine of the class described having, in combination, means for pulling an upper over a last, means for holding the upper to the last after the pulling operation, said holding means operating also to support the last during the upper securing operation, and means for locking the holding means in holding and supporting position.

8. A pulling-over machine having, in combination, a plurality of grippers for pulling an upper over a last, means for holding the upper to the last after it is pulled and while it is being fastened, and means for automatically locking the holding means against backward movement while it is doing its work.

9. A pulling-over machine having, in combination, a plurality of grippers for pulling

an upper over a last, a plurality of last supporters that also clamp the upper against the last while the pulled upper is being secured, and means for automatically locking the supporters against depression while they are doing their work and subsequently unlocking them.

10. A pulling-over machine having, in combination, a plurality of grippers for pulling an upper over a last, means movable laterally from and toward the shoe and to be raised into position to rest the shoe, and means for automatically locking the shoe resting means in raised position and for unlocking it when it is moved laterally away from the shoe.

11. A machine of the class described having, in combination, means for pulling an upper over a last, and upper clamping and shoe supporting means at opposite sides of the shoe each comprising a plurality of connected shoe engaging members that are relatively movable to adapt themselves to the shape and position of the last, and means for locking them in their position of adaptation to enable them to resist displacement of the shoe.

12. A machine of the class described having, in combination, mechanism for pulling an upper over a last, means to clamp the pulled upper against the side of the last in the line of strain effected by the pulling means, and independently actuated means for clamping against the innersole an adjacent portion of said pulled upper located in the line of strain.

13. A machine of the class described having, in combination, grippers for pulling an upper over a last simultaneously from opposite sides, oppositely acting means for clamping the pulled upper against the two sides of the last in the lines of strain produced by the pulling means, means operated independently thereof to clamp the marginal edge of same portion of the upper against the bottom of the last, and means operating in time relation with the latter clamping means to release the grippers.

14. A machine of the class described having, in combination, grippers for pulling an upper over a last simultaneously from opposite sides, means for clamping the pulled upper against the sides of the last, means for tacking the upper, and wipers movably mounted on the tacking means to lay the upper over the shoe bottom in advance of the tackers.

15. A machine of the class described having, in combination, grippers for pulling an upper over a last simultaneously from opposite sides, means for clamping the pulled portions of the said upper against the sides of the last, means arranged to advance inwardly from opposite sides of the last for tacking the upper while under tension, and

- wipers yieldingly movable endwise under each of the tacking means to lay the upper down with a rubbing movement and adapted to assist the side clamps to hold the upper when the grippers release it and arranged then to advance over the upper ahead of the tacker.
16. A machine of the class described having, in combination, grippers for pulling an upper over a last simultaneously from opposite sides, means for clamping the pulled upper against the sides of the last in the lines of strain produced by the pulling means, including a clamping member to engage the side of the shoe near the edge of the last in said line of strain, a wiper arranged to assist said clamping member to form the upper in said line of strain over the edge of the last, and means for advancing said wiper independently of the clamp before the grippers release the upper and then further advancing it inwardly over the last bottom after the grippers release the upper.
17. A machine of the class described having, in combination, a gripper, a clamp, a wiper, said clamp and wiper being arranged to operate on the upper in the line of strain produced by the gripper and actuating mechanism therefor having provision for causing the clamp and the wiper to coöperate to secure the upper before the grippers release it and for thereafter advancing the wiper over the last bottom while the clamp continues to hold the upper.
18. A machine of the class described having, in combination, a gripper, a clamp, a wiper, a tacker, and actuating mechanism therefor having provision for causing the clamp and the wiper to coöperate to secure the upper before the grippers release it and for thereafter advancing the wiper and the tacker over the last bottom with the wiper moving faster than the tacker to lay the upper for the operation of the tacker.
19. A machine of the class described having, in combination, a gripper, a clamp, a tacker, and a wiper all arranged to act on the upper in the same line of pulling strain, said wiper being arranged to move at times with the tacker and to have at other times endwise movement relatively to the tacker.
20. A machine of the class described having, in combination, a wiper, and a carrier movable to advance the wiper to do its work and to retract the wiper, said machine having provision for additionally retracting the wiper automatically.
21. A machine of the class described having, in combination, a wiper, a carrier that is actuated to advance the wiper, a spring holding the wiper to the carrier to cause it to move therewith, and means for automatically relieving the wiper from the control of the spring when the carrier is retracted.
22. A machine of the class described having, in combination, the carrier 42, the wiper 40, the spring 56 arranged to hold the wiper normally forward on the carrier, and means, 58, 60 for relieving the pressure of the spring when the carrier is retracted, as and for the purpose stated.
23. A machine of the class described having, in combination, a carrier, and a wiper mounted thereon to permit independent movements of the wiper, a spring arranged to resist such movements, and means for automatically relieving the wiper from the control of the spring at times.
24. A machine of the class described having, in combination, a last bottom rest, a gripper to pull an upper against the resistance of the rest, a last support movable upwardly and inwardly into supporting engagement with the side of the shoe while the gripper is holding the upper under tension and thereby pressing the last upwardly against the bottom rest, means for releasing the grippers from the upper, and means for locking the last supporters against downward and outward movement by the downward reaction of the last when the grippers release the upper.
25. A machine of the class described having, in combination, a last bottom rest, a gripper to pull an upper against the resistance of the last, a last support, and means for moving said support while the gripper holds the upper obliquely in an upward and inward direction against the side of the shoe whereby the upper engaged by it is pressed in the same direction that the gripper is pulling it.
26. A machine of the class described having, in combination, a last bottom rest, a gripper to pull an upper against the resistance of the last, a last support, means for moving said support while the gripper holds the upper obliquely in an upward and inward direction against the side of the shoe, and means to release the grippers from the upper while the upwardly inclined last support is in engagement with the upper on the side of the shoe whereby the downward reaction of the last and bottom rest effects a tightening of the upper between the last and the supporter, substantially as described.
27. A machine for working an upper over a last having, in combination, grippers to seize an upper, means to lay the upper over the shoe bottom, a shoe bottom rest having a downward movement to depress the last for stretching the upper and positioning the feather of the insole in the plane of action of the overlaying means, and last supporting means having an upward movement to clamp the shoe against the bottom rest and coöoperating with said rest to control the position of the shoe during the over-laying operation.

28. In a machine of the class described the combination with a last supporter arranged to engage the side of an inverted shoe by a movement inwardly and upwardly 5 toward the plane of the shoe bottom, of means arranged to engage the side of the shoe in advance of the supporter and connected therewith to transmit movement to the supporter.
29. In a machine of the class described 10 the combination with side clamps arranged for movement into engagement with opposite sides of an inverted shoe, of last supporters arranged for movement therewith 15 and to engage the shoe after the side clamps have made engagement therewith, for the purpose described.
30. In a machine of the class described 20 the combination with side clamps arranged for movement into engagement with opposite sides of an inverted shoe, of last supporters arranged for subsequent movement inwardly and upwardly into supporting engagement with a lower portion of the shoe 25 than that engaged by the side clamps.
31. In a machine of the class described 30 the combination with yieldingly mounted side clamps, of a last supporter connected with each clamp for movement thereby into engagement with the shoe after the side clamp has engaged the shoe.
32. In a machine of the class described 35 the combination with opposed yieldingly mounted side clamps and opposed last supporters, and upwardly and inwardly inclined guides in which the last supporters are arranged with their acting faces normally back of the acting faces of the side clamps, said supporters being connected 40 with the clamps to be forced thereby upwardly and inwardly into supporting engagement with the shoe.
33. A machine of the class described having, in combination, the side clamp 25, the 45 last supporter 15, the connecting pinion 20 and a spring operatively arranged in the line of connection between the clamp and supporter in position to maintain the clamp 50 in position to engage the shoe before the supporter engages the shoe.
34. A machine of the class described having, in combination, an arm movable toward and from the shoe to be operated upon and having an inclined guideway, a last supporter 55 mounted in said guideway, and means arranged to become operative automatically during the final portion of the approach of the supporter to the shoe for actuating the supporter upwardly and inwardly in said 60 guideway in the arm.
35. A machine of the class described having, in combination, a last supporter, a carrier by which it is moved toward the work and in which the supporter is also movable 65 in a direction inclined upwardly and inwardly toward the work, a feeler connected with the supporter to effect the last mentioned movement, and means predetermining the relative position of the feeler and the supporter to cause the feeler first to contact with the work and by such contact be caused to drive the supporter relatively to its carrier upwardly and inwardly against the shoe.
36. A machine of the class described having, in combination, the last supporter 15, its carrier 10, and means for actuating the supporter into operative position including means to actuate it upwardly and inwardly 70 against the shoe to do its work, and means for securing the last supporter rigidly against depression by force transmitted through the last.
37. A machine of the class described having, in combination, the side clamp, the last 80 supporter, the connecting means between said clamp and said supporter, and means for locking said parts.
38. A machine of the class described having, in combination, the side clamp, the last 85 supporter actuated thereby, and means for automatically locking the last supporter against depression.
39. A machine of the class described having, in combination, the side clamp, the last 90 supporter actuated thereby, and means for automatically locking the last supporter against depression while said parts are in working relation to the shoe, and automatically 95 unlocking the supporter when said parts are moved away from working relation.
40. A machine of the class described having, in combination, means for positioning a shoe to be operated upon, means movable 100 yieldingly into place for supporting the shoe against depression from such position, and means arranged to lock said supporter against retraction while in engagement with the shoe and thereafter automatically 105 unlocking it.
41. A machine of the class described having, in combination, a last supporter, and a side clamp arranged to force the last supporter 110 into operative relation to the shoe 115 after the clamp reaches an operative position.
42. A machine of the class described having, in combination, a last supporter, a side clamp arranged to force the last supporter 120 into operative position, and means to lock the last supporter against retrograde movement.
43. A machine of the class described having, in combination, a last supporter, and 125 means to lock the last supporter against reverse movement, said machine having provision for automatically unlocking the supporter.
44. A machine of the class described hav-

- ing, in combination, a last supporter and a side clamp, a ratchet connected with one of said members, a gravity pawl normally engaging the ratchet to lock the last supporter against reverse movement and adapted to be momentarily moved automatically out of such engagement, and a spring to retract the last supporter while the ratchet is free to turn.
45. A machine of the class described having, in combination, an upper contacting member, a pinion connected therewith, and a lower contacting member arranged to engage the shoe after the upper member and to be driven through said pinion upwardly as well as inwardly into such engagement.
46. A machine of the class described having, in combination, members movable successively into engagement with the shoe to support it and comprising an upper member, and a lower member connected therewith and arranged to be driven through said connection upwardly and inwardly into engagement with the shoe only after the upper member has first engaged the shoe.
47. A machine of the class described having, in combination, members movable successively into engagement with the shoe to support it and comprising an upper member, a lower member connected therewith and arranged to be driven through said connection upwardly and inwardly into engagement with the shoe only after the upper member has first engaged the shoe, and means for locking the lower member against reverse movement while it is in supporting engagement with the shoe.
48. A machine of the class described having, in combination, members movable successively into engagement with the shoe to support it and comprising an upper member, a lower member connected therewith and arranged to be driven through said connection upwardly and inwardly into engagement with the shoe only after the upper member has first engaged the shoe, and means to hold the upper member in position to engage the shoe before the lower member engages it.
49. A machine of the class described having, in combination, opposed side clamps at opposite sides of the median line of the shoe, opposed last supporters similarly disposed, means for actuating said devices into holding relation to the shoe, and means for locking the last supporters.
50. A machine of the class described having, in combination, opposed last supporters mounted at opposite sides of the median line of the shoe, means for actuating said supporters into operative position, and means for automatically locking the supporters against reverse movement.
51. A machine of the class described having last supporters which are movable lat-

erally from opposite sides of a shoe toward holding relation thereto in combination with carriers in which the supporters are movable to adapt themselves to the particular shoe to be supported, and means for automatically locking the supporters against depression while they are upholding the shoe.

52. A machine of the class described having, in combination, a last supporter, a carrier, means for moving the supporter automatically in its carrier to last supporting position, means for locking the supporter against reverse movement in the carrier, and means for automatically unlocking the supporter.

53. A machine of the class described having, in combination, a last supporter, a carrier, means for moving the supporter automatically in its carrier to last supporting position, means for locking the supporter against reverse movement in the carrier, and means for retracting the carrier and supporter together from the shoe and automatically unlocking the supporter during such retraction.

54. A machine of the class described having means to hold the upper while pulling means gives place to fastening means or during the securing operation, said holding means comprising upper and lower members the latter of which is movable obliquely upward from its normal position, and operative connections through which they are movable in relation to one another, the upper member being adapted to engage the shoe first and thereby, through said operative connections cause the lower member to be forced obliquely upward into contact with the shoe for the purpose described.

55. A machine of the class described having, in combination, shoe supporting means at opposite sides of the shoe which comprise a plurality of connected shoe engaging members that are relatively movable to adapt themselves to the shape and position of the last, and means for locking said members in their position of adaptation to enable them to resist displacement of the shoe.

56. A machine of the class described having, in combination, a carrier, a side clamp and a last supporter each movably mounted in the carrier, an equalizer connecting said clamp and supporter, a ratchet operatively connected with the equalizer, and a pawl arranged to engage said ratchet to lock it and the equalizer against movement in the direction in which pressure on the last supporter would tend to move it.

57. A machine of the class described having, in combination, a carrier, a side clamp and a last supporter each movably mounted in the carrier, an equalizer connecting said clamp and supporter, means for holding said parts in position for the side clamp to engage the shoe before the last supporter en

gages the shoe and to transmit movement through said equalizer for projecting the last supporter toward the shoe, and a ratchet and a pawl arranged to lock the last supporter automatically against backward movement.

In testimony whereof I have signed my

name to this specification in the presence of two subscribing witnesses.

RONALD F. McFEELY.
